JAMES H. KNAPP, OF BEVERLY HILLS, CALIFORNIA, ASSIGNOR TO JAMES H. KNAPP CO., OF LOS ANGELES, CALIFORNIA, A CORPORATION OF CALIFORNIA

CAR TYPE FURNACE

Application filed July 30, 1930. Serial No. 471,733.

My invention relates to furnaces and relates particularly to a furnace having certain important features of construction and operation which make it particularly useful in 5 the ceramic art.

At the present time furnaces are used extensively in the ceramic art for burning tile. One particular use of furnaces is for burning decorative tile, or, in other words, burning 10 the enamel coated thereon in order that the enamel may be fixed or glazed. In view of the fact that in present furnaces a rapid change in temperature will crack the tile, the 15 cycle of operation is relatively slow, consequently the efficiency, so far as rate of production is concerned, is relatively low.

It is one of the objects of my present invention to provide a furnace in which the cycle of operation is much faster than in the 20 ordinary type of batch furnace.

It is a further object of my invention to provide a furnace in which the temperature throughout the heating chamber or treating chamber is dependably uniform.

25 It is a still further object of my invention to provide a furnace in which it is possible to rapidly cool the tiles without cracking them. This object of my invention is accomplished by designing the furnace so that a 30 cooling gas, such as air, may be introduced in such a manner that the tile is evenly cooled. I have found that the reason for the breakage of the tile is that if it is removed from the furnace while it is at a comparatively high 35 temperature the cooling is uneven, and for this reason the breakage occurs.

It is another object of my invention to provide a furnace having means for passing air through the side walls of the furnace, thus 40 assisting in the cooling operation. These passages in the side walls do not communicate with the interior of the furnace but are located between inner and outer portions of the furnace walls.

45 It is another object of my invention to provide a furnace in which the cooling medium, which is preferably air, is introduced into the combustion chamber and passes from the combustion chamber into the treating chamber where the articles being burned are pres-

ent. In this manner the cool air is warmed before it passes to the treating chamber. As the air is passed through the combustion chamber and through the treating chamber, the heat is evenly and uniformly removed 55 from the combustion chamber and the treating chamber and consequently the temperature in the treating chamber will be reduced without sufficient shock to the material to crack it. In this arrangement of my invention the cooling air is first warmed or pre-heated in the combustion chamber, and as the heat is taken from the combustion chamber the passing air is warmed less, and consequently the air passing into the treating 60 chamber is uniformly cooler and thus uniformly reduces the temperature throughout the treating chamber.

A further object of my invention is to provide a furnace of the type referred to in which 70 the combustion takes place behind a bridge wall. This bridge wall is made of a material which becomes incandescent and the articles in the treating chamber are heated principally by radiation.

75 Another feature object of my invention is to provide a furnace of the car type in which the car when placed in the furnace provides a central flue through which the hot gases may escape.

80 A very important part of the invention resides in the arrangement of a central treating chamber and side combustion chambers on each side thereof, and a central vent for the gases, this vent, in the preferred form of my 85 invention, being located in the car.

Another object of the present invention is to provide a method of burning or treating tile, preferably decorative tile, in which the enamel or glazed surface retains the colors in 90 their natural form and is comparatively brilliant.

95 This object of my invention is accomplished by performing in the heat-treating process the step of immediately and rapidly cooling the tile when the melting temperature of the glaze or enamel has been reached. I have found that if the temperature in the furnace is maintained at the melting temperature of the glaze or enamel, that the 100

enamel will lose its luster and the colors will be unnatural and will be dull.

Another object of my invention is to provide a method of heating a charge to a desired temperature and then quickly and evenly cooling such charge without removing same from the heating device and without causing the charge to crack or be warped or otherwise injured, such as results when an uneven cooling occurs.

It is a further object of my invention to provide a furnace of the character mentioned having a car on which the articles to be treated are placed which may be conveniently and readily charged and discharged; that is, the articles may be easily placed on and removed from the car.

In the preferred form of my invention, I accomplish this object by forming the setters as a part of the car rather than separately, as is the present practice. In my invention the setters remain intact and only the articles are handled, which eliminates considerable labor in loading and unloading.

Further objects and advantages of the furnace of my invention reside in the details of construction and in the description which is to follow. These various objects and advantages will be pointed out in connection with the structure.

Referring to the accompanying drawings,—

Fig. 1 is a longitudinal view through my invention.

Fig. 2 is a longitudinal section showing the means for cooling the walls of the furnace and showing the interior of the combustion chamber.

Fig. 3 is a cross-sectional view through my invention.

Fig. 4 is an end view thereof partly in section.

Referring to the drawings in detail, the numeral 11 represents a foundation on which the furnace proper is supported. The furnace has a floor 12 which rests on the foundation 11. Extending upward from the floor 12 are side walls 13 and end walls 14. Supported at the upper ends of these walls 13 and 14 is a curved top wall 15. Formed in the foundation 11 longitudinally of the furnace is a cavity 17, and formed in the floor 12 above the cavity 17 is a longitudinal opening 18. Formed in the end walls 14 of the furnace are entrances 20 which are adapted to be closed by vertically slidable doors 22.

The numeral 23 indicates a car which is adapted to be moved into the furnace. The car 23 has a horizontal body 24 which is supported on wheels 25, which wheels 25 operate on tracks 26 placed in the bottom of the cavity 17. The body 24 is longer than the furnace and ends 27 thereof extend through the entrances 20 to the exterior of the furnace.

Extending upward from the body 24 are walls 28 which rest in the entrances 20 when the car is placed in the furnace and therefore close these entrances and assist in retaining the heat in the furnace. Arranged between the walls 28 in two sections 30 are setters 31 which support articles 32 which are to be heat-treated, or, in the case of decorative tile, burned.

Extending upward from the floor 12 adjacent the side walls 13 are bridge walls 34 which are made of heat resisting and heat conducting material such as carborundum. As shown best in Fig. 3, the bridge walls 34 terminate below the top wall 15. These bridge walls 34 divide the interior of the furnace into a central treating chamber 36 and side combustion chambers 37. Formed horizontally through the side walls 13 and connected to the lower parts of the combustion chambers 37 are openings 38 which receive burners 39. These burners 39 supply the combustion chambers with a combustible gas and combustion supporting gas in order that a flame may be produced in the combustion chambers. The gases of combustion are removed from the furnace through a central flue 41 which is formed longitudinally in the body 24 of the car 23. This flue 41 extends longitudinally of the car body and the treating chamber 36, and the ends thereof are connected to cross-flues 42 provided in the ends 27. The end portions of the cross-flues 42 are joined to vertical flues 43 which are in communication with stacks 44 which in the present embodiment of my invention are connected to the doors 22. Suitable sealing means, such as 45, is provided where the stacks engage the end portions 27 of the body of the car in order to prevent leakage. It will be noted that the width of the body of the car is substantially that of the opening 18.

Therefore, the body acts as a closure for one portion of the entrance 20. The portion of the entrance 20 above the body of the car is closed by the door 22, the lower end of which is adapted to engage the upper face of the body of the car when the parts are in the positions shown in the drawings. The treating chamber 36 is connected to the flue 41 by series of longitudinally arranged openings 47. These openings 47 communicate with the lower part of the treating chamber 36 between the sections 30 of the setters supported on the car.

When it is desired to heat treat articles, such as 32, they are placed on the car 23 in the setters 31, as illustrated, prior to the time that the car is placed in the furnace. The doors 22 are removed to elevated positions and the car is moved on the tracks 26 until it reaches the position shown in Fig. 1. At this time the doors 22 are lowered in order to close the entrances 20 in order to bring the stacks into engagement with the ends of

the car. The burners are then set into operation and a flame is produced in each of the combustion chambers 37. The combustion chambers are made separate from the treating chamber in order that combustion will take place away from the articles to be treated and in order to prevent carburation of them. The combustion taking place in the combustion chambers heats the bridge walls 34 to an incandescent heat, which heat radiates towards the central vertical plane of the treating chamber and thus heats the articles 32 by radiation. The products of combustion pass upward from the combustion chamber, as indicated by arrows 50, and pass inwardly over the top of the bridge walls 34 to the upper part of the treating chamber 36. The products of combustion then pass downward, as indicated by arrows 51, between the sections 30 and pass outward through the openings 47 into the flue 41. The hot gases therefore assist by convection in heating the articles 32. It will be noted that these hot gases come into contact with the portions of the articles 32 which are most remote from the bridge walls 34 and therefore assist in obtaining and maintaining an even temperature.

When the furnace is being used for burning decorative tile, which use is the principal use of my invention, the temperature is raised to the melting point of the enamel which is coated on the decorative tile. The manner of manufacturing decorative tile is well known, and one of the steps consists in painting enamel on the surface of the tile, which enamel must afterwards be burned in order to smooth it out and to make it hard.

In my furnace the temperature is raised to the melting point of the enamel. In view of the specific arrangement illustrated, the temperature at all points of the treating chamber is the same. Therefore, the enamel on all pieces of tile is liquefied at the same time. When the enamel is liquefied, it will flow on the surface of the tile and become smooth. I have discovered that a better quality of decorative tile is produced when it is cooled immediately after the melting temperature of the enamel is reached. This is probably because of the fact that while the enamel is in a liquid state some chemical change or evaporation takes place which deprives the enamel of its true color and luster. The furnace of my invention is very quickly cooled by the following means and in the following manner.

As shown best in Fig. 2, the end walls 14 are provided with cooling gas passages 55 which connect to the ends of the combustion chambers 37 at the lower parts thereof. The outer ends of the cooling gas passages are closed by suitable valve plates 56. If desired, a conduit may be connected to the cooling gas passages 55 and suitable flow-causing means

employed to force cooling air through the cooling gas passages into the combustion chambers. When it is desired to cool the furnace and the articles 32 therein, which is the case in decorative tile, immediately after the melting temperature of the enamel is reached the burners 39 are shut down and the valves 56 of the cooling gas passages 55 are opened. Cooling gas, which in the present instance is air, will flow into the ends of the combustion chambers 37 either by the draft effect of the furnace or by a mechanical flow creating means, and this cooling air, because it first passes into the combustion chambers, derives a certain amount of heat therefrom and its temperature is raised. This cooling gas then flows through the same path as described in connection with the products of combustion and in passing through the treating chamber cools the articles 32 therein. As the cooling gas continues to flow through this cycle, the temperature in the combustion chambers 37 is reduced and the bridge wall 34 is cooled. It will be seen that as the operation goes on the air which reaches the treating chamber 36 gradually becomes cooler because of the fact that the heat taken on in the combustion chamber is less as the cooling operation continues. In a relatively short period of time the temperature in the treating chamber and the temperature of the articles 32 are sufficiently reduced so that the articles can be exposed to atmospheric temperature without danger of cracking, and the doors are then elevated and the car is removed.

The cooling operation is an important part of the invention. It is quite important to the operation of the furnace that the cooling air be introduced into the combustion chambers. The reason for this is that the cooling air is preheated in order that the change in temperature in the treating chamber 36 may not be too sudden, and in order that the articles 32 will not receive a shock by a stream of cold air flowing into contact with them. The first cooling air which passes into the treating chamber 36 is but slightly cooler than the temperature in the treating chamber, but as the cooling operation continues the cooling air which flows into the treating chamber becomes gradually cooler and cooler until the temperature has been sufficiently reduced to permit the articles to be brought into contact with atmospheric temperature.

I also provide an additional means for cooling the furnace. This means constitutes vertical cooling passages 60 which are formed in the side walls 13. The lower ends of the cooling passages 60 connect to the exterior at 61 and the upper ends connect to the exterior at 62. These passages 60 are shown in Fig. 3 and are shown in the left-hand part of Fig. 2. Valve means 64 and 65 are provided for the passages and are opened only when

the cooling operation is taking place. When the cooling operation is taking place the valves 64 and 65 are opened and a flow of cooling air or gas will flow through the cooling passages 60, thus reducing the temperature of the walls.

In the preferred form of my invention, as shown herein, the setters 31 form an integral part of the car. Horizontal plates 80 made from a heat-resistant material are supported in spaced relation by blocks 81 which are made from a heat-resistant material. The parts may be secured together so as to be a part of the car by a mortar cementing material. The articles 32 are placed on the plates 80 and removed in a horizontal direction. The setters are never removed from place, which reduces to a considerable extent the labor of charging and discharging the car. Furthermore, a breakage of one of the plates will not disturb the others.

In the foregoing description I have described and in the drawings I have shown the preferred form of my invention. I have mentioned the use of my furnace in connection with the ceramic art and particularly in connection with the manufacture of decorative tile. I wish it to be understood that I do not intend to limit myself to the specific details shown and described, nor do I intend to limit myself to a furnace which is capable of use only in the ceramic art. I fully understand that my invention is useful in other arts wherein the features and advantages provided by my invention are of value.

I claim as my invention:

1. In a furnace of the class described, the combination of: walls forming a treating chamber and an entrance therefor; means for heating said treating chamber; and a car adapted to be placed in said treating chamber, one end of said car being adapted to extend through said entrance, said car having a flue through which the gas passes from said treating chamber, the exhaust end of said flue being in the end of said car which projects through said entrance.

2. In a furnace of the class described, the combination of: walls enclosing a space; bridge walls extending upward in said space and forming said space into a central treating chamber and side combustion chambers, said chambers being connected together at their upper ends; heat-producing means for said combustion chambers; and a car adapted to be moved into said treating chamber, said car providing a flue near the central part of said treating chamber.

3. In a furnace of the class described, the combination of: walls defining a treating chamber; walls forming a combustion chamber, and including a radiation wall between said treating chamber and said combustion chamber; means for supporting a charge in said treating chamber adjacent said radia-

tion wall, so that said charge may be heated by radiation; combustion means in said combustion chamber for heating said radiation wall, there being flue means connected to said combustion chamber and said treating chamber for directing hot gas from said combustion chamber into adjacency with the portion of said charge remote from said radiation wall; and means for directing a cooling gas into the lower part of said combustion chamber, said cooling gas passing through said flue means and into contact with said charge, and said cooling gas continuously taking heat from said radiation wall.

4. In a furnace of the class described, the combination of: walls defining a treating chamber; walls forming a combustion chamber, and including a radiation wall between said treating chamber and said combustion chamber; means for supporting a charge in said treating chamber adjacent said radiation wall, so that said charge may be heated by radiation; and combustion means in said combustion chamber for heating said radiation wall, there being flue means connected to said combustion chamber and said treating chamber for directing hot gas from said combustion chamber into adjacency with the portion of said charge remote from said radiation wall, and there being a cooling passage in said walls forming said treating chamber and said combustion chamber, said cooling passage having an inlet and outlet in communication with the exterior of said furnace.

5. In a furnace of the class described, the combination of: walls defining a treating chamber; walls forming a combustion chamber, and including a radiation wall between said treating chamber and said combustion chamber; means for supporting a charge in said treating chamber adjacent said radiation wall, so that said charge may be heated by radiation; combustion means in said combustion chamber for heating said radiation wall, there being flue means connected to said combustion chamber and said treating chamber for directing hot gas from said combustion chamber into adjacency with the portion of said charge remote from said radiation wall, and there being a cooling passage in said walls forming said treating chamber and said combustion chamber, said cooling passage having an inlet and outlet in communication with the exterior of said furnace; and means for directing a cooling gas into the lower part of said combustion chamber, said cooling gas passing through said flue means and into contact with said charge, said cooling gas continuously taking heat from said radiation wall.

In testimony whereof, I have hereunto set my hand at Los Angeles, California, this 26th day of July, 1930.

JAMES H. KNAPP.
